ELECTRIC GOVERNOR

Filed Oct. 13, 1925

Fig. 1.

Patented Oct. 25, 1927.

UNITED STATES PATENT OFFICE.

HAROLD KENNETH WHITEHORN, OF MAIDSTONE, ENGLAND, ASSIGNOR TO TILLING-
STEVENS MOTORS LIMITED, OF MAIDSTONE, KENT, ENGLAND.

ELECTRIC GOVERNOR.

Application filed October 13, 1925, Serial No. 62,268, and in Great Britain October 28, 1924.

This invention relates to electrical governors and is more particularly intended to be applied to a governor intended to regulate the throttle of an engine driving a 5 dynamo.

There have of course been a number of proposals for controlling an engine driving a dynamo by means of an electroresponsive device operating on the engine throttle, 10 the majority of such devices being spring or gravity controlled and electro-magnetically moved against the action of the controlling force.

It is an object of the present invention to 15 provide an improved device wherein an electro-magnetic governor assumes positions fixed in accordance with the ratio of current to electro-motive force in the dynamo circuit and the principal feature of the invention lies in the windings energized respectively according to the volts and amperes of the dynamo circuit being arranged in different magnetic axes. In the preferred device 20 an increase of voltage tends to close the throttle, and increased current tends to open the throttle relatively to its ordinary mean 25 position for normal running.

The invention comprises further novel features, combinations and arrangements 30 embodied in the preferred forms of this apparatus hereinafter described and specifically pointed out in the claims.

In one such form the invention may be 35 applied to a vehicle of the petrol-electric or like type including a dynamo driven by an engine and a motor arranged to drive the vehicle and supplied with current from the dynamo. Illustration is afforded by the accompanying drawings wherein:—

40 Fig. 1 is a plan view of a preferred form of governor attached to the throttle valve of such an engine.

Fig. 2 is a sectional elevation, and

Fig. 3 shows an alternative form of yoke

45 and windings.

The governor comprises a rotary armature 1 mounted within a yoke 2 having both shunt and series windings so arranged that the shunt and series components are 50 respectively applied at different magnetic axes corresponding to (but not necessarily coinciding with) the two extreme governed positions of the throttle. For example, as shown at Fig. 2 there may be two main 55 poles 3 opposite to one another and pro-

vided with a shunt winding 4 so as to be strengthened by any increase of voltage between the dynamo terminals. In addition two auxiliary poles 5 are provided opposite to one another and preferably having their axes angularly spaced at some 30 to 50 degrees from the axes of the main poles. The auxiliary poles 5 have a series winding 6 traversed by the main dynamo current (or a proportion thereof) so that an increase of the main current tends to strengthen the auxiliary poles. A single shoe 7 may extend across the faces of each pair of like main and auxiliary poles so that in effect a zone of maximum resultant magnetic flux travels along the shoe in accordance with the varying ratio between dynamo voltage and dynamo current. A coiled spring 8 or the like may be employed to balance or steady the action of the device and will preferably be so set as to help to open the throttle when the latter is nearly closed and a drop in voltage takes place, since in such cases the drop may be such as to prevent the load from increasing 80 to the necessary degree to give immediate relief to the engine by an immediate and sufficient opening of the throttle. The connection of the armature to the throttle valve 9 by lever arms 10 and 11 is clearly shown at Fig. 1.

In another preferred form shown at Fig. 3 the yoke may be built of laminations and the poles slotted to receive distributed windings, the resultant magnetic axes AA 90 and BB of the shunt and series components 4 and 6 respectively being separated by a suitable angular distance.

The oscillating armature 1 may in either case be unwound or preferably symmetrically wound with a shunt winding or with some turns of both shunt and series winding 12 and 13, so that it will assume an angular position corresponding to the position of the maximum resultant flux. It will however be clear that an angular spacing of shunt and series components may be employed upon the armature as well as or instead of on the yoke. Moreover, the air gap may be tapered so as to define the exact 105 position that will be taken up by the armature under various conditions. It is desirable that the various parts be skewed in relation to the mechanical axis, more particularly in the forms having distributed 110

winding to give an even gradation of the flux.

To prevent hunting effects all movement may be suitably damped by dashpot or copper bar instead of or in addition to the use of the coiled spring 8.

The operation of the device will be apparent from the above description.

It will be observed that when additional load comes on the motor, there is normally a tendency to slow down the engine, with the result that the dynamo voltage tends to fall and at the same time more current is required. The governor responds to this tendency to drop voltage by opening the throttle and keeping up the engine speed to whatever may be necessary to maintain the voltage and supply the necessary current. The coiled spring may preferably be set to bring the throttle to its mean position or rather more open than the mean position when the dynamo is not generating, or may tend with decreasing force to draw it to the fully open position. In this manner the engine speed is automatically governed in accordance with the load, and the throttle is kept open just to the necessary extent to supply the voltage and current being utilized by the system at any particular time.

30 The governed throttle may of course be auxiliary to an ordinary hand- or foot-controlled throttle.

I claim:

1. An actuating element for electric engine governors comprising a pair of relatively oscillating members, shunt and series windings relatively asymmetrically arranged

upon one of said members and shunt and series windings relatively symmetrically arranged upon the other of said members.

2. An actuating element for electric engine governors, including two relatively oscillatory members having magnetic axes which tend to coincide to determine the relative angular positions of the members, windings on one of said members energized respectively in accord with the voltage and amperage of a dynamo circuit in different angular spaced magnetic axes.

3. An actuating element for electric engine governors, including a yoke and an armature arranged for relative oscillation, the yoke having a shunt-wound pole and a series-wound pole angularly spaced relative to one another, whereby the position of the resultant magnetic flux may vary within an angle dependent upon the spacing.

4. In an actuating element as defined in claim 3, the provision of a yoke having a pair of shunt-wound poles and a pair of series-wound poles, the magnetic axes of the respective pairs of poles intersecting one another at a suitable angle.

5. An actuating element as in claim 3, wherein the armature is symmetrically wound with both shunt and series windings.

6. An actuating element of the type defined in claim 3, wherein the yoke is provided with a pair of shunt-wound poles and a pair of series-wound poles, and a shoe common to like poles.

In testimony whereof I affix my signature.

HAROLD KENNETH WHITEHORN.
